(57) **CLAIM**

The ornamental design for a case for refillable leads for a mechanical pencil, as shown and described.

DESCRIPTION

FIG. 1 is a top, front and left perspective view of a case for refillable leads for a mechanical pencil showing our new design;

FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof;

FIG. 7 is a top plan view thereof with the cap opened;

FIG. 8 is a bottom plan view thereof with the cap opened;

FIG. 9 is a left side elevational view thereof with the cap opened;

FIG. 10 is a front elevational view thereof with the cap opened;

FIG. 11 is a right side elevational view thereof with the cap opened;

FIG. 12 is a sectional view thereof taken along line 12—12 in FIG. 5;

FIG. 13 is a sectional view thereof taken along the line 13—13 in FIG. 2; and,

FIG. 14 is a sectional view thereof taken along line 14—14 in FIG. 7.
